US0D1114031S

(12) **United States Design Patent** (10) **Patent No.:** **US D1,114,031 S**
(45) **Date of Patent:** **** Feb. 17, 2026**

(54) **HOLOGRAM PROJECTOR**

(71) Applicant: **INTERMAN Corporation**, Kagoshima (JP)

(72) Inventors: **Shigeki Uetabira**, Kagoshima (JP); **Yoshimasa Saitoh**, Machida (JP); **Yoshihiro Mikami**, Kyoto (JP); **Katsuhiko Torii**, Tokyo (JP)

(73) Assignee: **INTERMAN Corporation**, Kagoshima (JP)

(**) Term: **15 Years**

(21) Appl. No.: **35/521,091**

(22) Filed: **May 29, 2023**

(80) **Hague Agreement Data**

Int. Filing Date: **May 29, 2023**

Int. Reg. No.: **DM/230010**

Int. Reg. Date: **May 29, 2023**

Int. Reg. Pub. Date: **May 31, 2024**

(30) **Foreign Application Priority Data**

Jan. 29, 2023 (JP) ..... 2023001413 D

(51) **LOC (15) Cl.** **16-02**

(57) **CLAIM**

The ornamental design for a hologram projector as shown and described.

DESCRIPTION

1. Hologram projector

1.1: Front

1.2: Back

1.3: Top

1.4: Right

1.5: Perspective

1.6: Folded view

The left side view is a mirror image of the right side view and is therefore omitted. The broken lines throughout the figures depict portions of the hologram projector that form no part of the claimed design.

1 Claim, 6 Drawing Sheets
